UNITED STATES PATENT OFFICE.

JOHN F. OHMER, OF DAYTON, OHIO, ASSIGNOR TO OHMER FARE REGISTER COMPANY,
OF DAYTON, OHIO, A CORPORATION OF NEW YORK.

TRANSFER PRINTING AND ISSUING MACHINE.

1,182,410.

Specification of Letters Patent.

Patented May 9, 1916.

Application filed January 11, 1915. Serial No. 1,806.

To all whom it may concern:

Be it known that I, JOHN F. OHMER, a citizen of the United States, residing at Dayton, in the county of Montgomery and State of Ohio, have invented certain new and useful Improvements in Transfer Printing and Issuing Machines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in machines for printing and issuing extemporaneous traffic tickets, such as transfers, to be used on street cars to enable passengers to transfer from one street car line to another. Heretofore, it has been the common practice for conductors to carry a pad of previously printed transfers which require to be punched at various points thereon to indicate the various data necessary to the proper issuance thereof. This system is subject to much annoyance, the consumption of time and needless expense and affords an opportunity for the improper use of transfers.

The main object of this invention is, therefore, to provide a machine which will print and issue a transfer from a strip of paper unwound from a roll contained therein, the said transfer so printed and issued containing all the necessary data, for example, the date of its issuance, together with the month and the year, also the direction of the passage which it covers and other matter which is printed from a fixed type plate, such for example, as the name of the company issuing the transfer, etc.

A further object of the invention is to provide a machine of this character from which transfers may be issued rapidly and accurately by the conductor with his foot so that the passenger can take possession of the transfer after it has been printed, issued and severed by the machine, or the machine may be operated by means of a hand lever.

Another object of the invention is to provide a machine of this type wherein transfers are printed from a continuous roll of paper with the necessary time limitation controlling their use so that in order to ob-

tain the benefit of such transfers the passengers receiving the same will be required to take the next available car on the line upon which the transfers are intended to be used within the time limitation noted thereon, thereby preventing the transfers being made to serve the purpose of a stop-over privilege.

To the above ends the device consists of the various mechanisms to be hereinafter described in connection with the accompanying drawings and pointed out in the claims.

Referring to the accompanying drawings, Figure 1 is a perspective view of my improved transfer printing and issuing machine. Fig. 2 is a side elevation showing the same mounted upon a pedestal. Fig. 3 is a view of a transfer as issued from the machine. Fig. 4 is a front elevation of the machine. Fig. 5 is an elevation of the right side of the machine viewing the same in Fig. 4. Fig. 6 is a view of the left side of the machine as viewed in Fig. 4. Fig. 7 is a section on the line 7—7 of Fig. 4. Fig. 8 is a section approximately on the line 8—8 of Fig. 7. Fig. 9 is a detail view of the paper-severing and holding means. Fig. 10 is a detail view of the identification and machine-locking key. Fig. 11 is a detail view of the means for separating the paper-feeding rolls. Figs. 12 and 13 are detail views of the means for supporting the roll of paper. Fig. 14 is a detail view of the inking-roll-carrying-frame. Fig. 15 is a detail view of the platen-controlling-mechanism. Fig. 16 is a detail view of the platen. Fig. 17 is a detail view of the platen-alining means.

Throughout the specification and drawing, similar reference characters indicate corresponding parts both in the specification and drawings.

*The frame work, (Figs. 1, 4, 5, 6, 7 and 8)—*The supporting frame-work may be varied more or less from that shown; that shown, however, is a suitable construction for properly housing the various mechanisms. As shown in Fig. 1, it consists of two side plates 21 and 22 which are united at the bottom by a stay-bolt 23 at an intermediate point by a cross-frame 24 and at the top by a plate 25. The frame thus constructed and assembled is mounted on a suitable base 20 and supports the mechanism of the machine described as follows under appropriate headings.

- The type or printing wheels, (Figs. 4, 7 and 8.)*—Mounted upon the cross-frame 24 is a frame 26 provided with a shaft 27 upon which the various type wheels are mounted.
- 5 As seen from Fig. 4, to the right of the frame 26, are three date-printing wheels 28, 29 and 30, wheel 28 being the month wheel and wheel 29 being the day of the month wheel. The wheels 28 and 29 are provided with gears 31 and the same are manually set from the outside of the machine through the agency of index drums 32 and telescopic shafts 35. The wheel 30 is the year-printing wheel and the same is provided with gear 16 wheels 33. The said wheels 28, 29 and 30 are held in their set positions by spring-pawls 34. The year wheel 30 is set manually from the inside of the machine and requires to be set but once a year. To the left of the 20 date-printing wheels, as seen from Figs. 4 and 8, is a bank of printing wheels 36 which print the consecutive numbers on the transfers. The wheels 36 are provided with transfer gears 37 mounted upon a shaft 38.
- 25 The unit wheel of said printing wheels 36 is actuated by means of a ratchet 39 adapted to be engaged by a pawl 40 on a swinging arm 41. The means for swinging or actuating the arm 41 will be hereinafter described.
- 30 Mounted in the frame 26 and to the left of the consecutive number-printing wheels 36 is a printing wheel 42 having characters thereon to print on the transfers the directions of travel such, for example, as north, south, east or west. To the left of the wheel 42 is a wheel 43 having characters thereon adapted to print on the transfers the time abbreviations "A. M." or "P. M.". To the left of the wheel 43 is a printing wheel 44 having characters thereon adapted to print on the transfers the minutes of the hours at which the transfers are issued, or the time in which the transfers are to be used. To the left of the wheel 44 is a printing wheel 45 having characters thereon adapted to print on the transfers the hours, the same to be read in connection with the minute indications printed from wheel 44. All of the foregoing printing wheels 42, 43, 44 and 45 are provided with suitable transfer gears 46 and the same are manually set from index drums 47 and telescopic shafts 48. The index drums 32 and 47 are mounted on the outside of a casing 49 which incloses the various mechanisms, as will be seen from Fig. 1. All of the printing wheels above described are adapted to print the changeable data on the transfers along a line designated by 75, seen in Fig. 3. To print upon the transfers the unchangeable data or matter, such for example, as the name of the railway company issuing the transfers, a fixed printing plate 76 is mounted upon the frame 26 beneath the printing wheels, as will be seen from Figs. 4 and 7. In order to indicate upon the transfers whether they are issued on a full passage or a half fare passage, a printing block 134 is vertically and slidably mounted in the frame 26 between the consecutive numbering and the direction 70 printing wheels 36 and 42, respectively. The said printing block 134 may be shifted vertically into and out of the printing positions by a rod 135 which extends upwardly and out of the casing 49 where it is provided with a button 136 by means of which said block may be manually shifted. When the said block is shifted out of a printing position, a blank space is left on the transfer which indicates that it is for a full fare passage, and when the said block is moved into a printing position it prints on the transfer the designation "1/2" which indicates that the transfer is for a half fare passage, as shown on the transfer in Fig. 3.
- 80 *The paper feeding mechanism, (Figs. 4, 7, 8, 12 and 13.)*—Supported within guides 50 on the inside of the side plates 21 and 22 is a frame 51. Removably mounted in this frame 51 is a spindle 52 upon which a roll of paper 53 is mounted, the same being supported on the shaft 52 through the agency of hubs 54. The said roll of paper rotates on the shaft 52 but is held against a too free unwinding by a semi-circular friction piece 55. The friction piece 55 is pivoted at 56 to the frame 51 and bears against one of the hubs 54, being pressed against the hub by a spring 57. The friction between the piece 55 and the hub 54 90 is sufficient to prevent the roll of paper 53 unwinding too freely. The paper strip 58 from the roll 53 passes upwardly in front of the printing wheels mounted in the frame 26 and the fixed printing plate 76 and between upper feed rollers 59 and lower feed rollers 60. The upper rollers 59 are the tension rollers mounted on a shaft 61, while the lower rollers 60 are the actual feeding rollers mounted upon a shaft 62. The shaft 61 is journaled in slidble members 63 mounted in guides 64 at the top and on the outside of the side plates 21 and 22. The said slidble members 63 are under the control of springs 65 which are instrumental in pressing the feeding rollers 59 and 60 together. The lower shaft 62 is journaled in bosses 66 in the side plates 21 and 22. On the left end of the shaft 62, as seen from Fig. 6, the said shaft 62 is provided with a gear 67 in mesh with a larger gear 68 mounted upon a stud 69 attached to the side plate 21. The gear 68 carries a pawl 70 in operative relation with a ratchet 71 attached to a pinion 72 also mounted upon the stud 69. The pinion 72 is in mesh with a vertically movable rack 73 mounted in a guide 74 attached to the side plate 21. The means for actuating the rack 73 will be described under the heading "Actuating 100
- 110
- 115
- 120
- 125
- 130

means." The feeding rollers 59 and 60 are separated to permit of the insertion of the paper strip by cam levers 117 fulcrumed upon a shaft 118 and provided with finger extensions 119. The said cam levers 117 are shown in detail in Fig. 11 and are provided each with a recess 120 to receive the shaft 61 and to thereby maintain said feed rollers in a separated position when the finger extensions 119 are depressed. In order to conveniently indicate on the outside of the casing the varying diameter of the roll of paper 53 and to thus ascertain the number of transfers a roll of paper is capable 15 of supplying, there is pivoted in the plate 21, as is shown in Fig. 7, a stud-shaft 137. Mounted upon the inner end of said stud-shaft 137 is an arm 138 which bears by gravity upon the periphery of the roll of 20 paper. The said shaft 137 extends out of the casing 49 and on its outer end is provided with a pointer 139 which cooperates with indications 140 on the casing 49; see Fig. 1. As the diameter of the roll of paper 25 decreases, the pointer 139 will move to indicate the number of transfers capable of being issued from the paper roll.

The platen mechanism, (Figs. 4, 7 and 8.)—A roller platen 77, constructed of any 30 suitable material such, for example, as rubber, is adapted to press the paper strip 58 against the printing devices. The said roller platen 77 is mounted upon a shaft 78 and is carried by side frames 79 provided 35 with horizontal recesses 80 which receive the shaft 78 and permit said platen to move horizontally. The side frames 79 are connected by a cross-rod 81 and are vertically movable on rails 82 extending from plates 83. The plates 83 are secured to the inside of the side frames 21 and 22 by bolts 84 and are adjustably set thereon by means of screws 85 for a purpose hereinafter specified. Mounted upon both plates 83 are 40 plates 86 having recesses therein which, together with an intermediate raised portion 87 thereof and pivotal guide tongues 89, form an ascending race 90 and a descending race 91, as shown in Figs. 7 and 15. The ends 45 of the platen-carrying-shaft 78 extend beyond the side frames 79 and travel in the races 90 and 91. When the said frames 79 are elevated, by means hereinafter described, the roller platen 77 is carried upwardly with the ends of the shaft 78 traveling in the ascending race 90 until the platen reaches the end of its upward movement when the ends of the shaft 78 will pass in the descending race 91. When the said 50 roller platen 77 initially ascends, the ends of the shaft 78 engage the lower guide tongue 89 and act as cams to move the roller platen 77 horizontally and to a position to press the paper against the type faces when the said platen reaches the upper end of its 55

travel. During the upward movement of the said platen the guide tongues 89 swing on their pivots 92 to permit the ends of the shaft 78 to pass said tongues, but when said platen reaches the end of its upward movement the upper tongues 89 fall beneath the shaft 78 and subsequently guide the ends of said shaft into the descending race 91 at which time the platen is lowered. When the roller platen reaches a point near 60 the bottom of the descending race 91, the shaft 78 thrusts aside the lower guide tongues 89 which assume normal positions above the shaft 78 when said platen reaches its normal position and the said lower guide 65 tongues are then in a position to guide the shaft 78 into the ascending race 90 at which time the platen is elevated. The normal position of the guide tongues 89 is shown in Fig. 7 and said tongues are held in such 70 position as follows:—The said tongues 89 are pivoted at 92 and are provided with short cranks 93 which are shown in detail in Fig. 15. The cranks 93 are provided with pins 94 which extend through curved 75 openings 95, best shown in Figs. 5 and 6. The pins 94 are connected to springs 96 which lie in pockets 97 formed in the side frames 21 and 22. The springs 96 exert no influence on the pins 94 to hold the guide 80 tongues 89 in their normal position.

Prior to the pressing of the paper strip 58 against the type faces, the said type faces are inked by an inking roll 98 carried with the platen. The inking roller 98 is mounted upon a shaft 99 which in turn is mounted in swinging side plates 100 pivoted on the shaft 78 and provided with downwardly projecting arms 101 having pins 102 thereon; see Fig. 14. When the inking roller 98 is in engagement with the type faces, the plates 100 are rocked to bring the pins 102 in engagement with pivotal arms 103 mounted on the side frames 79. The arms 103 are under the control of springs 104 and 105 are instrumental in pressing the inking roller 98 against the face of the type. The said inking roller 98 is further provided with a guard or shield consisting of a curved plate 105 which is mounted on end plates 106 pivoted at 107 to the side plates 100. The plates 106, in addition to supporting the shield 105, are instrumental in holding the shaft 99 of the inking roller in position within the plates 100. The shaft 99 lies in recesses 108 in the plates 100 and are held therein by the end plates 106, as will be seen in detail from Fig. 14. After the shaft 99 is in position within the recesses 108, it is held 110 therein by the end plates 106 which are in turn locked in position by pins 109 which extend through the plates 100 and 106. In order to prevent the inking roller 98 from being used the pins 109 are extended to permit the shield 105 to be thrown upwardly. 115

and the shaft 39 to be removed from the recesses 108, as shown in Fig. 14. The paper strip 58 passes between the shield 105 and the roller platen 77, thereby protecting the paper strip from the inking roller 98 and enabling the said platen to press the paper against the printing type and devices.

In order to reduce the diameters of the time and day of the month printing wheels 44 and 29 to the desirable extent, the printing characters thereon are comparatively close together and there is some liability of impressions being taken from parts of those characters above and below the characters from which it is desired to print, when the platen roller passes over the selected type. In order to prevent this, the roller platen 77 is provided at each end with longitudinal peripheral recesses 110. These recesses 110 provide platen surfaces 111 which are approximately of a width equal to the height of the type on said printing wheels. The roller platen at these points can only press the paper strip against the selected type. In order to rotate said roller platen during the printing operation, it is provided with gears 112 on the ends thereof, which mesh with vertical racks 113 mounted upon brackets 114 suspended from the plates 83. Before the gears 112 mesh with the racks 113, the platen is positioned by a spring 115 mounted upon a bracket 116 supported from one of the plates 83. The spring 115 is biased to engage one of the gears 112 which for this purpose is provided with a plurality of faces corresponding in number to the platen end surfaces 111, as is clearly shown in Fig. 17, Sheet 1. During the subsequent toward movement of the platen, the gear slides along the surface of the spring 115 until it meshes with its rack 113 at which time it will begin to rotate. The parts are so proportioned and timed as to bring the platen end surfaces 111 in engagement with the said printing type 44 and 29 during the subsequent upward movement of said platen. The pressure exerted against all the devices by the platen may be regulated by adjusting the plates 83 by the screws 85 and are held in position by bolts 84, before referred to.

The paper severing and cutting means, (Figs. 7 and 9.) Extending across the top of the machine and mounted upon the side plates 21 and 22, is a plate 25, before referred to. This plate 25 is provided with an elongated longitudinal opening 121 through which the paper strip 58 passes after leaving the feed rollers 59 and 60. The plate 25 is provided with guides 122 in which a severing knife 123 is mounted. The knife 123 is provided with a cutting edge 124 which operates in connection with one edge of the elongated opening 121 in severing the

paper strip into the requisite transfers. The said knife is actuated to cut the paper by springs 125 which are connected to suitable studs on the knife and on the guides 122. The knife is actuated against the tension 126 of the springs and is moved to a position to uncover the elongated opening 121 by a lever 128 pivoted upon the shaft 38. The means for actuating said lever and for releasing the same to permit the springs 125 to actuate the knife to sever the paper will be described under the heading "Actuating means". Also mounted in the guides 122 is a plate 127 which rests directly upon the knife 123 and cooperates with a plate 129 in forming a clamp to hold the transfers in position to be removed by passengers after they are severed. Each transfer issues from the machine through an opening 130 in a casing 49, shown in Fig. 1. The plate 127 is pressed against the plate 129 to clamp the transfer by means of springs 131 which are connected to suitable studs on the plate 127 and to the guides 122. The plate 127 is removed from engagement with the plate 129 to permit of the free passage of the paper strip by pins 132 carried by the knife 123 and which engage the ends of the elongated openings 133 in the plate 127, as shown in Figs. 4 and 9. During the retrograde movement of the knife 123, the pins 132 engage the ends of the slots 134 and remove the plate 127 from engagement with the plate 129.

The identification and locking key, (Figs. 1, 4, 5, 8 and 10.)— Mounted on the cross-frame 24 is a key-housing 141 which receives a removable key 142. The said key 142 is provided with printing characters 143 on its inner end which are inked by the inking roller 98 to print upon the transfer, as seen from Fig. 3. The printing characters 143 upon said key designate the operator or conductor and each conductor of the railway system is provided with one of such keys 142 with his individual identification mark thereon. To prevent the machine being operated when the key 142 is extracted from the housing 141 and to lock the machine when the key 142 is inserted, the following means are provided:—The key 142 is provided with projections 144 which are adapted to rock a bell-crank-lever 145 when said key is inserted and withdrawn; see Fig. 10. The lever 145 is pivoted at 146 and is provided with a projection 147 which is connected to a link 148 which is best shown in Fig. 6. The link 148 is also connected to a bell crank-lever 149 pivoted at 150 to the side plate 22. The said bell-crank-lever 149 is connected by means of a link 151 to the crank 152 which extends from the shaft 118, before referred to. The shaft 118 is mounted in suitable bearings 153 on the side frames 21 and 22. Mounted upon

the shaft 118 are deflecting arms 154 the lower ends of which are adapted to engage shoulders 155 on bosses 156 extending from the side plates 79 which carry the roller platen 77. The shaft 118 is rocked when the key 142 is inserted and withdrawn. The said shaft is rocked to place the lower ends of the arms 154 in the path of the shoulders 155 when the key 142 is extracted, but upon the insertion of said key one of the projections 144 will rock the lever 145, shift the link 148, rock the bell-crank-lever 149, shift the link 151, rock the shaft 112, and shift the arms 154 to place the lower ends of the said arms 154 out of the path of the shoulders 155, thereby permitting the side frames 79 to be elevated and the machine to be operated. It will be noted that when the roller platen 77 is in an elevated position the shape of the arms 154 is designed to prevent the key 142 from being extracted because the arms 154 cannot move to a position above the shoulders 155 when the platen and frames 79 are in an elevated position, consequently, the machine cannot be operated when the key is extracted and the key can be extracted only at such times when the machine is in a normal condition.

The actuating means, (Figs. 2, 4, 5, 6 and 7.)—Attached to the rod 81 which connects the frames 79 is a clamp 163 provided with a bracket 157 from which downwardly extends a rod 158. The rod 158 extends down through a pedestal 159 upon which the machine is mounted. The pedestal 159 is provided with a base plate 160 having a pivot-bearing 161 upon which a tread lever 162 is mounted. One end of the lever 162 is adapted to be engaged by the foot of the operator or conductor, while the other end thereof is connected to the lower end of the rod 158. When the free end of said lever is pressed downwardly, the rod 158, rod 81, side plates 79, and roller platen 77 will be elevated. The impact of the reciprocating mechanism due to the operation of the foot treadle may be cushioned by any suitable means such for example as a dash pot shown within the pedestal in Fig. 2 and consisting of an air cylinder 186 suitably connected to the pedestal 159 at 189, the same being provided with a piston and rod extension 187 connected at 188 to the operating rod 158. During this movement of the roller platen, the paper feeding devices, the paper severing devices, and the consecutive numbering counter are actuated. The paper feeding devices are actuated during the initial downward movement of the roller platen by the following means:—The rod 81, as seen from Figs. 4 and 6, extends past the base 159 of the left plate 79. The left end of said rod 81 lies in a slot 164 in a lever 165 pivoted at 166 to the side plate 79; see Fig. 6. The said lever 165 is provided with an irregular slot 167 which receives a roller 168 mounted upon the lower end of the arm 169 attached to the rod 79. When said lever 165 is elevated by the rod 81, the catchet 71 rocks freely upon the platen 77, but when 70 said lever 165 is lowered it permits the catchet 71 to rock the platen 77 and extract the arms 68, 69, and the locking rods 20 and 21, thereby feeding the paper. Subsequent to the feeding of the paper and during the ascending movement of the roller platen 77, the knife 128 is given a movement to uncover the opening 121 in, below, the right end of the rod 81, as seen from Figs. 2 and 6, lies in the slot 164 of the side plates 79 and 22 pivoted at 170 to the side plate 22. Attached to said lever 171 and its pivot 172 is a segment gear 173 which is in mesh with a segment gear 174 on the outer end of shaft 170 pivoted in the side plates 79 and 22. At an intermediate point, the shaft 170 is provided with an arm 175 adapted to engage the lower end 176 of the lever 126 to move the knife 128 from above the opening 121, thereby permitting the paper strip to pass through the opening 121. When the lower end 176 of the lever 126 is thus actuated by the arm 175, it is caught by a spring-latch 178 and is held in such position until after the feeding of the paper. 95 At this time said latch is caused to release the lever 126 to permit the knife spring 125 to actuate the knife 128 to sever the paper, by the arm 173 carried by the shaft 170. During the ascending movement of the roller piston, the shaft 170 is rocked in one direction to permit the arm 176 to rock the lever 126. During the downward movement of the platen, the shaft 170 is rocked in a direction to permit the arm 176 to trip 105 the latch 178 and to thereby release the lower end 176 of the lever 126, thereby placing the knife 128 under the control of the spring 125 and severing the paper strip. 110.

The consecutive number printing wheels 36 are actuated during the downward movement of the roller platen and after the printing operation by a crank 189 mounted upon the shaft 170. The crank 189 is provided with a slot 191 which receives a roller stud 188 on the lower end of the actuating arm 41 of the consecutive numbering wheels. The consecutive numbering wheels 36 are held in their various positions by rollers 193 which engage the teeth of the transfer gears 37 themselves and which are controlled by springs 194.

While the machine illustrated and described may be used for any and all purposes to be operated by hand, it is also provided with a printing and feeding apparatus and the like, it will be readily understood that it is intended principally for use in a printing office and to be operated by the hand without making any material change or al-

teration in the mechanism thereof; such adaptation is well within the scope of the invention.

Mode of operation.—Prior to the placing 5 of the machine in operation, the tension of the roller platen against the type faces is adjusted by the regulating screws 85 and the year printing wheel 30 is set by gaining access to the interior of the machine. Prior to 10 the placing of the machine in operation upon a car, the roll of paper 58 is mounted upon the spindle 52 and the said spindle is placed in its position in the frame 51 which is in turn inserted in the guides 56 within the 15 machine. The strip of paper 58 is then passed between the roller platen 77 and the guard 105 and is then drawn upwardly and inserted between the feed rollers 59 and 60, said feed rollers being separated by the cam levers 117. The paper is then projected through the opening 121 in the plate 25 and out through the opening 130 in the casing 49. When the conductor takes charge of the car, he inserts his identification key 142 within 20 the housing 141 which operation rocks the levers 145 and 149 and moves the lower ends of the arms 154 out of the path of the shoulders 155 on the plates 79 which carry the roller platen. The conductor then sets the 25 month and day printing wheels 28 and 29 by rotating the drums 32, and sets the "A. M." and "P. M." indications on the type wheel 43 by rotating the respective drum 47, the drums 32 and 47 being read in connection 30 with pointers 185. When the conductor desires to issue a transfer, he rotates the time and direction drum 47 to bring their respective printing wheels into proper printing position and shifts the button and the 35 type block 144 to a position to indicate either a full fare or a half fare. He then presses downwardly the foot lever 162 which operation elevates the rods 178 and 81, the plates 79, the roller platen 77, and the inking roll 98. During the upward movement of said platen, the type of the identification key 142, the type of the plate 36, and the type of the printing wheels are inked by the roller 98, and the paper strip 58 is pressed against the 40 inking type by the roller platen 77, thereby printing a transfer. Also, during the upward movement of the roller platen 77, the shaft 175 is rocked through the agency of the lever 171 in a direction to permit the 45 arm 176 to rock the lever 126 to permit the knife 123 to uncover the opening 121, thereby permitting the paper strip to be subsequently fed by the rollers 59 and 60. During the downward movement of the roller platen, the 50 shaft 62 of the paper feeding roll is actuated through the agency of gears 67 and 68, ratchet 71, pinion 72, rach 73, and the lever 165 connected to the rod 81. During the subsequent downward movement of said roller 55 platen, the shaft 175 is rocked by the lever 60

171 to permit the arm 179 to trip the latch 158 to release the lever 126, thereby allowing the spring 125 to actuate the knife 123 to sever the paper strip. When said knife 123 is moved to sever the paper strip, the plate 70 127 in connection with the plate 129 grips the severed transfer and holds the same in a position where it may be easily removed by the passenger. Simultaneous with this operation, the arm 180 on the shaft 175 rocks the 75 arm 41 of the consecutive numbering counter, thereby actuating the same. When the conductor leaves the car, he extracts his key 142 which act shifts the lower ends of the arms 154 in the path of the shoulders 155, thereby 80 locking the machine.

While I have with some particularity described the various mechanism involved in my invention, I do not wish to be limited to any unessential specific details as it will be readily understood that these may be changed or varied within the scope of the 85 claims.

Having described my invention, I claim.

1. In a machine for printing and issuing 90 extemporaneous tickets or transfers, the combination with a printing member, of a laterally and vertically reciprocable platen adapted to engage said printing member during the vertical movement, a pivotal arm movable with said platen, and means actuated by said arm whereby said printing member is actuated.

2. In a machine for printing and issuing 100 extemporaneous tickets or transfers, the combination with a transfer-consecutive-number-printing counter, of a roller platen adapted to receive both horizontal and vertical reciprocable movements, frames carrying said roller platen, an arm loosely connected to one of said frames and movable with said platen during the vertical movement thereof, a shaft geared to said arm, and actuating mechanism for said number printing counter interposed between said 105 shaft and said counter.

3. In a machine for printing and issuing 115 extemporaneous tickets or transfers, the combination with paper severing mechanism and a consecutive printing counter, of a platen adapted to receive horizontal and vertical reciprocable movements, frames carrying said roller platen, an arm, loosely connected to one of said frames and movable with said platen during the vertical reciprocable movement thereof, means interposed between said arm and said paper severing mechanism, and means interposed between said printing counter and said arm whereby 120 said paper severing mechanism and said printing counter are actuated from the movement given said arm from the platen.

4. In a machine for printing and issuing 125 extemporaneous tickets or transfers, the combination with a platen adapted to re- 130

ceive both horizontal and vertical reciprocable movements, frames carrying said platen, of paper feeding mechanism, an arm connected to one of said frames and movable with said platen, and means interposed between said arm and said paper feeding mechanism whereby the paper is fed during the operation of said arm from the platen.

5. In a machine for printing and issuing extemporaneous tickets or transfers, a shiftable platen, frames carrying said platen, arms connected to said frames and movable with said platen, a consecutive-number-printing counter and paper severing devices controlled by one of said arms and paper feeding devices controlled by the other of said arms, and mechanism interposed between said paper severing devices and consecutive-number-printing counter and one 20 of said arms respectively, and means interposed between the paper feeding mechanism and the other of said arms whereby said paper severing devices and consecutive-number-printing counter and said paper feeding mechanism are actuated during the vertical reciprocable movement of the platen.

6. In a machine for printing and issuing extemporaneous tickets or transfers, the combination with a shiftable roller platen, an arm 171 having a pin and slot connection with the platen supporting frame, a shaft 175 geared to said arm, a paper cutting knife 123, a lever 126 connected with said knife, an arm 176 on the shaft 175 in the path of an end of the lever 126 and whereby said lever 126 is rocked to elevate the knife from said shaft 175, a pivotal detent 178 arranged to engage said lever 126 to hold it when thus operated, and an arm 179 on the shaft 175 40 adapted to rock the detent 178 to release its engagement with said lever 126 and permit said knife to lower.

7. In a machine for printing and issuing extemporaneous tickets or transfers, the combination with a printing counter, of a shiftable roller platen, an arm 179 having a pin and slot connection with the platen supporting frame, a rock shaft 175 geared to said arm, a crank 180 fixed to said shaft 175, a swinging arm 41 having a pin and slot connection with said crank, a shaft 38 upon which said arm is pivoted, ratchet devices actuated from said swinging arm, and gear connections interposed between said ratchet devices and said printing counter.

8. In a machine for printing and issuing extemporaneous tickets or transfers, the combination with a shiftable roller platen, an arm 165 having a pin and slot connection with the frame of said platen, a vertical reciprocable rack 73 having a pin and slot connection with said arm 165, and paper feeding mechanism geared to said rack.

9. In a machine for issuing an extemporaneous ticket or transfer which consists

of a printing member and an impression member between which a paper strip passes, feeding means for said paper strip, severing means for said paper strip and holding means for the tickets severed from said paper strip, and means for actuating said impression means, said feeding means and said severing means consecutively, and said holding means concurrently with said severing means.

10. In a machine for issuing an extemporaneous ticket or transfer, printing means and impression means between which a paper strip passes, feeding means for said paper strip, and severing means for said paper strip, holding means for the severed tickets mounted on and actuated concurrently with said severing means, and means for actuating said impression means, said feeding means and said severing means consecutively.

11. In a machine for issuing an extemporaneous ticket or transfer, printing means and a shiftable and rotatable impression means between which a paper strip passes, feeding means for said paper strip, severing means for said paper strip, and holding means for the ticket severed from said strip, means for actuating said impression means, said feeding means and said severing means consecutively and said holding means concurrently with said severing means.

12. In a machine for issuing an extemporaneous ticket or transfer, printing means and a shiftable and rotatable impression means between which a paper strip passes, feeding means for said paper strip, severing means for said paper strip including the lever 126, holding means for said paper strip mountable on and actuated by said severing means and actuated to its holding position by said lever, and means for actuating said impression means, said feeding means and said severing means consecutively.

13. In a machine for issuing an extemporaneous ticket or transfer, printing means, a rotatable and shiftable platen, a frame which is slidable throughout its length having ascending and descending races therein which impart a vertical and horizontal movement of said platen, and adjusting means for said frame whereby the tension between the platen and the printing means may be regulated.

14. In a machine for issuing an extemporaneous ticket or transfer which consists of a printing member, a rotatable platen which is horizontally and vertically movable, a frame having ascending and descending races therein which impart a vertical and horizontal movement to said platen, resiliently mounted tongues mounted in said races and controlling the movement of the platen, and adjusting means for said frame.

whereby the tension between the platen and the printing means may be regulated.

15. In a machine for issuing an extensible ticket or transfer which consists of a printing member, a rotatable platen which is vertically and horizontally movable, means for rotating said platen, a frame having an ascending and descending race therein which controls the horizontal and vertical movement of said platen, and resiliently mounted tongues mounted in said races and guiding said platen from one race to the other.

16. In a machine for issuing an extensible ticket or transfer which consists of a printing member, a rotatable platen which is horizontally and vertically movable, a rack and gear for rotating said platen, and a frame having an ascending and descending race therein which controls the horizontal and vertical movement of said platen, and resiliently mounted tongues mounted in said races and guiding said platen from one race to the other.

17. In a machine of the character specified, a printing key, a platen having a reciprocating movement, a locking member extending along the path of said reciprocating platen and actuated by said key, said locking member being adapted to lock said platen when the key is withdrawn and to lock the key in a printing position when the platen is actuated.

18. In a machine of the character specified, a printing key, a reciprocating platen, an arm extending along the path of said reciprocating platen, links and levers connecting said key and arm whereby said arm is actuated during the insertion and withdrawal of said key whereby said platen is locked by said arm when said key is withdrawn and the key is locked in a printing position during the actuation of the platen.

19. In a machine of the character specified, a printing key, a reciprocating platen, an elongated pivotal arm extending along the path of said reciprocating platen, links and levers connected to said pivotal arm and adapted to be actuated by said key to lock said arm whereby said platen is locked when said key is withdrawn and said key is locked in a printing position during the actuation of said platen.

20. In a machine of the character specified, a printing key, a platen, a reciprocating frame carrying said platen, an elongated pivotal arm extending along the path of said frame, said frame being provided with a shoulder adapted to be engaged by said arm to lock the platen and to engage said arm to lock the same, and connecting means between said arm and said key whereby said

platen is locked when the key is withdrawn and the key is locked in a printing position during the actuation of the platen.

65

21. In a machine of the character specified, the combination with a platen, of a key containing a printing character, locking devices interposed between said key and said platen whereby said platen is locked when said key is withdrawn and the key is locked in a printing position during the actuation of said platen.

22. In a machine of the character specified, the combination with a platen of a key, of a shiftable member actuated upon the insertion and withdrawal of said key, an angular lever actuated by said shiftable member, a depending arm adapted to lock the platen against movement when the key is withdrawn and to release said platen when the key is inserted, and a connection between said arm and the angular lever.

23. In a machine of the character specified, the combination with a platen, of a key having projections thereon, a rocking member engaged by said projection and movable upon the insertion and withdrawal of the key, a longitudinally reciprocable member actuated by said key upon its withdrawal or insertion, an angular lever to which said reciprocable member is connected, a swinging arm adapted to be shifted to positions to lock and unlock the platen according to the movement of said reciprocable member, and a connection between the angular lever and said swinging arm.

24. In a machine of the character specified, the combination with a reciprocable frame, a roller platen and an inking roller carried thereby, and means for shifting said platen laterally in said frame to printing and non-printing positions, of a key, and means controlling the movement of said frame, said means being operative to permit of the movement of said frame when the key is inserted, and operative to prevent the movement of said frame when the key is withdrawn.

25. In a machine of the character specified, the combination with a reciprocable frame, of a platen roller mounted thereon, means comprising pivotal guide tongues adapted to shift said platen laterally to and from printing positions when said frame is given an operative movement, means controlling the movement of said frame, and a key controlling the movement of said means.

In testimony whereof, I affix my signature, in presence of two witnesses.

JOHN F. OHMER.
